UNITED STATES PATENT OFFICE

GEORGE W. MACKENZIE, OF BEAVER, PENNSYLVANIA

DESIGN FOR A MOVABLE SIGNAL FOR AUTOMOTIVE VEHICLES

Application filed September 23, 1932. Serial No. 45,019. Term of patent 14 years.

To all whom it may concern:

Be it known that I, GEORGE W. MACKENZIE, a citizen of the United States, residing at Beaver, in the county of Beaver and State of Pennsylvania, have invented a new, original, and ornamental Design for Movable Signal for Automotive Vehicles, of which the following is a specification, reference being had to the accompanying drawing, forming part thereof, in which—Figure 1 is a top plan view of a movable signal

for automotive vehicles showing my new design with the supporting clamp shown in Figure 3 omitted for convenience of illustration; Figure 2 a front elevation; and Figure 3 a side elevation.

I claim:

The ornamental design for a movable signal for automotive vehicles, as shown and described.

GEORGE W. MACKENZIE.
